UNITED STATES PATENT OFFICE.

JOHN CIBOR, OF PROVIDENCE, RHODE ISLAND.

RING.

Application filed April 17, 1926. Serial No. 102,683.

This invention relates to an improved construction of finger ring; and has for its object to provide a ring of this character the finger-encircling portion of which may be 5 readily enlarged or extended to be passed over the knuckle of the wearer and which will then contract to fit the smaller portion of the finger where it joins the hand.

With these and other objects in view, 10 the invention consists of certain novel features of construction, as will be more fully described, and particularly pointed out in the appended claims.

In the accompanying drawings:

15 Figure 1 is a perspective view of a finger ring constructed in accordance with my invention.

Figure 2 is a perspective view of the head portion of the ring after it has been swaged 20 to provide spring abutments thereon.

Figure 3 is a perspective view showing the head member as bent into substantially its finished shape.

Figure 4 is a perspective view of the top 25 plate of the head member.

Figure 5 is an enlarged perspective view showing the end portion of the band member which extends into the head.

Figure 6 is a sectional side elevation of 30 the head and band member in assembled contracted position.

Figure 7 is a plan view of the resilient means or spring for contracting the band.

Figure 8 is a view similar to Figure 6 35 showing the band in expanded position.

It is found in practice that finger rings which are made of a size to fit the finger where finger rings are commonly worn at the point where the finger joins the hand 40 that oftentimes the band will not pass over the knuckle of the wearer and thus it is necessary to make the ring several sizes larger than an actual wearing fit, in order that the ring may be passed over the 45 knuckle into wearing position and in order that a more perfect fit may be obtained for the ring in its wearing position, I have constructed a band member which has one or both of its ends slideable relative to the head 50 or ornamental portion of the ring and provide resilient means by which the band may be opened up or extended to pass over the knuckle and which resilient or spring means may act to contract the band after it has

been passed over the knuckle to more perfectly fit the ring wearing portion of the finger; and the following is a detailed description of the present embodiment of my invention and showing one construction by which these advantageous results may be 55 produced:—

With reference to the drawings, 10 designates the head and 11 the band member of my expandible ring. This head member is herein illustrated at 12 in Figure 2 as being bent or formed into shape and is shown as being provided with upstanding abutments 13 which may be formed in any suitable manner but which are here illustrated as being formed by swaging the plate 12 between dies to draw up the abutments 13 integral therewith after which the plate is bent as illustrated at 14, Figure 3, into substantially channel shape having a bottom wall 15 and side walls 16 which are folded as at 17 to receive a top plate 18 with cooperating inwardly turned edges 19 which top plate may be slid into the grooves formed by the folding over of portions 17 and these inter engaging portions are firmly pressed together to prevent the top plate from being withdrawn from the bottom member 14.

The end portions 20 of the band member are pierced out as at 21 forming an abutment web 22 at the end of the band, and this end portion extends into and is housed in the head, as illustrated in Figure 6, and the abutments 13 of the head extend into the pierced opening 21 and serve to limit the relative movement of the band end and head. Between the abutment 13 and the web 22 a spring 23 is positioned tending to press the end portion 20 into the head towards each other and contract the size of the ring. I have also illustrated in Figure 6 this construction as duplicated at both ends of the band portion which is found preferable, but it is understood that where a very slight enlargement is desired but one end portion of the band and housing need be so constructed as to slide, and in which case the other end of the band may be secured to the housing in any desired manner.

The foregoing description is directed solely towards the construction illustrated, but I desire it to be understood that I reserve the privilege of resorting to all the mechanical changes to which the device is

susceptible, the invention being defined and limited only by the terms of the appended claims.

I claim:

- 5 1. A finger ring comprising a hollow head a single piece band member having an end with an opening therein extending into said head and slidably relatively thereto, an abutment carried by and within said head extending into said opening, and a spring acting between said abutment and band end portion to move said end into said head and contract the ring.
- 10 2. A finger ring comprising a hollow head, a single piece band member having separable ends slidably extending into said head from opposite sides thereof, said each end having an opening therein, a pair of abutments carried by and within said head and one extending into the opening in one of said band ends and the other extending into the opening in the other of said band ends, and springs in said openings acting between said head abutments and band for tending to cause said band ends to slide in said head
- 15
- 20
- 25

toward each other and contract the size of the ring.

3. A finger ring comprising a single piece band member having separable ends with an opening in each end portion spaced from the end wall thereof, a hollow head housing said separable ends and having integral abutments therein spaced from the ends of said housing and each extending into one of said openings in said band end portion, and springs acting between said head abutments and the end walls of the openings to slide said band ends toward each other in said housing and contract the ring.

4. A finger ring comprising a hollow head, a band member having an end with an opening therein extending into said head and slidably relatively thereto, an abutment carried by and within said head extending into said opening, and resilient means acting between said abutment and band end portion to move said end into said head and contract the ring.

In testimony whereof I affix my signature.
JOHN CIBOR.
